ABSTRACT OF THE DISCLOSURE

A watertight watch case having a casing over which fits a watch glass with a packing ring therebetween for watertightness, a ring threaded on the casing to clamp the watch glass over the casing rim, the improvement in the provision of a first additional packing ring between the clamping ring and the watch glass and a second additional packing ring between the clamping ring and the casing, the second additional ring standing above the threads on the clamping ring and the casing, in respect to the first additional packing ring between the watch glass and the casing.

The patent invention relates to a watertight watch case, especially for diver's watch.

This watch case is of the type comprising a casing, a watch glass, a clamping ring and a packing ring arranged between the glass and the casing.

An object of the invention is to prevent infiltration of water upstream of the packing ring between the watch glass and the casing and at the level of the clamping ring.

This object is attained, in a watertight watch case according to the invention wherein a first tightness means is provided between the watch glass edge and the casing upper rim, by the provision of a second tightness means to ensure water-tightness between the watch glass and the clamping rim, a third tightness means to ensure water-tightness between the clamping ring and the casing, the second and the third tightness means being located to prevent water infiltration into the casing upstream of the first tightness means.

The appended single figure of drawing is a partial view, in cross-section, of one embodiment of the invention constituting a case of diver's watch.

As illustrated, the case comprises a casing 10, a watch glass 11 having a peripheral edge bearing against the upper rim 12 of the casing and a clamping ring 13 having threads meshing with corresponding threads formed on a flange projecting above and outwardly of rim 12 whereby to press watch glass 11 against rim 12.

A packing ring 14 lodged into a corresponding recess of the casing ensures watertightness between the latter and the watch glass.

In order to guarantee an absolute watertightness of the watch case at low and high pressures, two complementary packing rings 15 and 16 are provided upstream of packing ring 14, at the level of the clamping ring 13. These watertightness packing rings are arranged between the clamping ring 13 and the watch glass 11 and the casing 10 respectively. The packing ring 15 protects the threaded meshing portions and the packing ring 16 prevents any infiltration along the edge of the watch glass

2

in the direction of the main watertightness packing ring 14.

The watch case besides comprises a device for indicating the decompression stages, the device being constituted by a rotating sight 17 mounted in an annular groove of the casing 10. This sight subjected to the action of a braking spring 18 is integral with a ring 19. The latter is locked into a recess of the sight and carries the necessary indications for the determination of the decompression stages in relation to the depth and duration of immersion.

Sight 17 by overlapping the edge of the watch glass 11, the clamping ring 13 and the casing 10, gives the watch case a particularly aesthetic aspect.

The invention is obviously not limited to the embodiment described and illustrated. Particularly the location of the complementary packing rings 15 and 16 may be modified, the essential being that these joints are located upstream of the main tightness joint.

What is claimed is:

1. A watertight watch case, especially for diver's watch, said case having a casing defining a peripheral upper rim, a watch glass having a peripheral edge fitting over said upper rim, a clamping ring, cooperating means on said clamping ring and on said casing to allow pressing of said glass against said casing rim and first tightness means to ensure watertightness between said watch glass peripheral edge and casing upper rim, characterized by the provision of

(a) a second tightness means to ensure watertightness between said watch glass and clamping ring;
(b) a third tightness means to ensure watertightness between said clamping ring and said casing;
(c) said second and third tightness means located to prevent water infiltration into said casing upstream of said first means.

2. A watch case as claimed in claim 1, wherein said cooperating means comprises a flange projecting above and outwardly of said casing upper rim; meshing threads formed on said flange and on said clamping ring and wherein said third tightness means is located so as to protect said meshing threads.

3. A watch case as claimed in claim 2, wherein said third tightness means is located outwardly of said meshing threads in relation to said first tightness means.

4. A watch case as claimed in claim 3, wherein said second and third tightness means generally normally stand on a common level with respect to said first tightness means.

5. A watch case according to claim 1, including a rotating sight mounted for rotation on said casing and carrying indications relative to decompression stages, the said sight mounted to overlap said clamping ring.
